UNITED STATES PATENT OFFICE.

FRED W. COVERT, OF WATERVLIET, NEW YORK, ASSIGNOR TO COVERT MANUFACTURING COMPANY, OF WATERVLIET, NEW YORK, A CORPORATION OF NEW YORK.

HAME-FASTENER.

1,102,476.

Specification of Letters Patent.

Patented July 7, 1914.

Application filed March 14, 1911. Serial No. 614,505.

To all whom it may concern:

Be it known that I, FRED W. COVERT, a citizen of the United States, residing at Watervliet, in the county of Albany and State of New York, have invented certain new and useful Improvements in Hame-Fasteners, of which the following is a specification, reference being had therein to the accompanying drawing.

16 This invention relates to hame-fasteners, the primary object being the provision of an improved type of fastener, neat in appearance, inexpensive to manufacture, efficient in operation, and one which is durable and of 15 increased strength.

In the art of hame-fasteners, it will be appreciated by those familiar with the same, that it has been found exceedingly difficult to entirely satisfy the trade with a fastener 20 which will be of a compact form and neat in appearance, and at the same time of a strength to withstand the heavy strain imposed thereupon, and it is desired by the present invention to provide such a fastener, 25 that is, one less bulky in design, relatively light, and one neat in appearance and exceedingly strong.

One of the important features of the invention resides in the provision of a main 30 or body part of a boxlike construction, simple to manufacture and cheap to produce, and at the same time, permitting of a relatively thin or compact article, it being within the contemplation of the invention to provide a 35 body part which may assume a position snugly about the collar and within the groove between the usual bead at the edge of the collar and the body part of the latter.

Also the invention includes an improved 40 form or type of hook carried by and connected to the body part, one which is of considerable strength in its make up, and which is further strengthened and reinforced by the body part of the fastener.

45 Further the invention embraces an improved type of operating lever, and associated link connections for the usual chain or flexible connection adapted to be coupled to the end of one of the hames.

50 Other improvements and the novel details in the construction and arrangement of parts, will be more particularly referred to hereinafter, and for a clear understanding of the invention reference should be had to 55 the accompanying drawing, which form a

part hereof, and wherein is disclosed, for the purpose of illustration, convenient and satisfactory embodiments of the invention.

In the drawing: Figure 1 is a side view of one of the preferred forms of the fastener applied to a collar; Fig. 2 is a side view of the same separated from the collar and with the locking lever in open position; Fig. 3 is an upper edge view; Fig. 4 is an enlarged elevation of the fastener with one of the side plates removed; Fig. 5 is a perspective view of the same; Fig. 6 is an enlarged detail view of the lever showing the engaging lip in position to be bent about the link, and Figs. 7 and 8 are detail views of modified forms of links adapted to be connected with the lever.

With more particular reference to the drawing, in which like reference characters relate to corresponding parts throughout the several views, the main or body part of the fastener is made up of two side plates 1 conveniently of relatively thin substantially flat metal, one edge of the body part being preferably slightly curved or segmental shaped as shown at 1^a, while the opposite edge has a substantially U-shape cutout portion 1^b intermediate of its ends constituting a recess or seat for a part of the operating lever to be described hereinafter.

85 A hook member is connected to one end of the body part and comprises a hook proper 2 conveniently curved as shown, and connecting with an extended upright part 3, and which said upright part is preferably 90 an integral extension of the hook and is provided with a tongue or flange 4 adapted to fit between the side walls 1 of the body part. The hook may be and preferably is rigidly held in place on the body part by 95 bolts or rivets 5 extending from side to side of the body part and through apertures in the tongue or flange 4. The tongue 4 is conveniently thin in cross section, say of substantially the same thickness as the side 100 walls 1 of the body part, whereby, when in position the thickness of the body part is not materially increased by the interposition of the tongue, and it is also noted that the tongue conveniently extends from top to 105 bottom of the body part, thereby constituting not only the spacing means for the side walls of the body part, but a substantial reinforce for the latter. The upright portion 3 of the hook member is preferably sub- 110

stantially of the same width as the body part as a whole, and extends from top to bottom thereof, and fits flat against the ends of the said walls 1 of the body part, 5 which said end wall is shown slightly inclined upwardly and inwardly toward the body part, the parts being constructed and arranged so that when the fastener is upon the collar and the device is in operation, the 10 strain upon the hook proper is resisted by the upright wall 3 from top to bottom, which latter is reinforced in turn by the backing afforded by the ends of the said walls 1 of the body part. Again the 15 strength of the hook is further increased by the tongue or flange 4, which it will be noted extends substantially at right angles to the plane of the upright wall 3 of the hook. This type of hook forms a very 20 rigid construction of strength and durability, and being an independent element is easily and cheaply produced. Also this independent construction of the hook makes possible the box-like type of body part, 25 and reduces the cost of production of the latter, since the side wall construction of the body part results in a reduction of the amount of metal consumed, with the incident saving of expense 30 and reduction in weight, and further the side walls can be cheaply and readily stamped into the required shape. Conveniently a relatively small spacing block 6 is positioned between what may be termed 35 the rear ends of the walls of the body part adjacent the upper edges of the latter the spacing block being held in position by a rivet 7 or the like.

The operating lever is conveniently 40 formed with a handle part 8 shaped to conform to the curvature of the forward lower edge of the body part and the hook, and projects beyond the latter. The handle is relatively flat so as to snugly fit against the 45 adjacent parts of the body part and hook when in locking position and the projecting end is slightly curved as shown in the general direction of the hook.

The lever has a thickened portion 9 adjacent the rear end thereof, which thickened 50 portion connects with the forward end of a relative thin tongue or projection 10 extending at substantially right angles to the plane of the handle part and of a width to loosely engage between the side walls of 55 the body part. Projecting through the side walls 1 adjacent the lower rear end of the latter is a pintle 11, and the tongue end 10 of the operating lever has an aperture 11^a 60 adapted to loosely engage over the pintle, whereby the lever as a whole is pivotally mounted on the body part. The thickened portion 9 of the lever has an inwardly extending tail piece 12 conveniently of the 65 same width as the handle portion of the le-

ver, which said lip or tail piece is of bendable metal. Adapted to be connected to the lever is a link member preferably comprising two stamped out sides 13 and an end bar 14. The sides 13 preferably bulge as shown 70 so as to readily pass over the pivotal bearing or support 11, and the securing means for the spacing block 6, while the forward end bar 14 of the link is conveniently round in cross section and is adapted to be pivotally supported on the lever, by exerting pressure on the yieldable or bendable lip or tail 12, and bending the latter about said end bar 14, so as to form a substantially closed though loose bearing for said link. 75 It will be noted that the said bearing for the link is reinforced by the extended tongue 10 extending at an angle to the plane of the operating lever. When in locking position the bent tail or tongue 12 and the end bar 80 14 of the link will lie within the U-shaped recess 1^b of the body part, the base of which constitutes a seat, and the opposite sides of which recess are conveniently inclined to 85 permit of the ready engagement and release of the lever from said recess. 90

One end of the link is open, the opposite sides of which link adjacent said end being apertured for the reception of an auxiliary link having a closed end 15 and inwardly converging sides 16 which latter have offset terminals 17 adapted to engage the apertures in the sides 13 of the first mentioned link. The ends of said offset portions 17 may be upset to the outside of the side 13 of 100 the first mentioned link, whereby to hold the link against separation. Conveniently the auxiliary link just described may be formed of a piece of wire bent upon itself to a substantially U-shaped formation, with 105 the offset terminals, which latter may be sprung into place in the apertures in the sides of the connected link. The auxiliary link is movable about the pivot formed by said offset terminals, which loosely fit in the 110 apertures provided in the sides of the connected link, whereby the respective link members together constitute a flexible connection which will more readily conform to the curvature of the collar. The converging 115 sides of the auxiliary link also prevent the chain 18 which is connected thereto from passing into the main link, or between the sides of the main link and the body part of the fastener, or otherwise interfering with 120 the free operation of the parts. The chain conveniently has an adjustable connection or coupling 19 with the end of one of the hames.

In normal or operative position the fastener will assume a position such as illustrated in Fig. 1, in which said figure, A is a section of a collar, the same having a beaded edge *a* forming a groove *a'* between said edge and the body portion of the col- 125 130

lar. Because of the box like structure and relatively flat makeup of the main or body part of the fastener, the same may assume a position within the groove a' of the collar with the curved or concave edge 1^a of the body part snugly fitting against the base of said groove. The flexible construction afforded by the links which are connected to the lever, permits the link to engage about the collar, as more clearly illustrated in Fig. 1. To release the parts the operator grasps the projecting end of the lever as is obvious and imparts downward movement thereto, when the lever will swing about its pivot and the various parts will assume a position more clearly illustrated in Fig. 2, and when the hook 2 may be readily disengaged from the end of the hame.

In Fig. 7 is disclosed a slightly modified form of flexible link connection between the lever and chain and in said figure the main link has a closed end 20 connected to the lever as desired and oppositely disposed sides 21, which converge at their ends as shown leaving a space therebetween for the reception of a collar 22 of an auxiliary closed link 23, which latter is adapted for connection with the chain. A bearing 24 conveniently having upset ends passes through apertures in the ends of the sides 21 of the link, and through the collar 22 of the auxiliary link, the bearing constituting a loose support for the auxiliary link. From this illustration it is obvious that the connected links may take various forms, such for instance as further illustrated in Fig. 8 in which the sides 21 a and closed end bar 20 a are provided as before. The auxiliary link 21 b in this form is substantially U-shaped and the arms thereof having apertures adapted to register with apertures in the sides 21 a of the first mentioned link. A bar or rivet 21 c loosely passing through said registering apertures and conveniently offset at its ends forms a pivotal connection between the links.

In each of the above forms it will be appreciated that the flexible character of the link connections permits a neater fit about the collar and at the same time the chain is held from interference with the parts when in operation.

What I claim is:

1. In a hame-fastener, a relatively thin body part of rigid construction comprising slightly separated side plates, a hook member having a part positioned between said plates adjacent one end thereof, rigidly secured to the latter and forming a spacing medium therefor, a lever also pivotally mounted between said side plates adjacent the opposite end thereof, means for connecting a chain or the like to said lever, and the side plates having cut out portions forming a receiving pocket for said means.

2. In a hame-fastener, a body part formed to provide a recess intermediate its sides, a lever pivoted to the body part, a hook comprising a curved body part having a flange intermediate its sides arranged to fit in said recess of the body part, means for securing the hook to the body part, a link having a pivotal connection with the lever, an auxiliary link, a chain on the auxiliary link, and means for pivotally connecting said links together whereby the chain is held in position. 70

3. In a hame-fastener, a body part formed to produce a recess intermediate its sides, a lever pivoted to said body part and arranged for connection to a chain or the like, and a hook having an extended body part substantially co-extensive with one end of the first named body part and arranged to fit against the latter and a flange projecting therefrom and arranged to fit in the recess of the body part. 80

4. In a hame-fastener, a body part comprising oppositely disposed sides, a hook having a part projecting between the sides 90 of the body part and secured to the latter, said projecting part of the hook being relatively thin and constituting a spacing medium for the sides of the body part, a lever having a relatively thin tongue to engage 95 between the sides at the opposite end of the body part and mounted on the latter for pivotal movement, and a link connected with the lever intermediate its ends.

5. In a hame-fastener, a body part comprising oppositely disposed flat sides, a hook having a part projecting between the sides of the body part and secured to the latter, said projecting part of the hook being relatively thin and constituting a spacing medium for the sides of the body part, a lever having a relatively thin tongue to engage 100 between the sides at the opposite end of the body part and mounted on the latter for pivotal movement, a link having opposite sides 105 and a bearing part at one end, said lever having a projecting tail or lip intermediate its ends bent about said bearing part to constitute a substantially closed but loose connection for the end of the link, and a chain 110 carrying member at the opposite end of the link. 115

6. In a hame-fastener, a body part comprising oppositely disposed flat sides, a hook having a part projecting between the sides 120 of the body part and secured to the latter, said projecting part of the hook being relatively thin and constituting a spacing medium for the sides of the body part, a lever having a relatively thin tongue to engage 125 between the sides at the opposite end of the body part and mounted on the latter for pivotal movement, a link having opposite sides and a bearing part at one end, said lever having a projecting tail or lip intermediate 130

its ends bent about said bearing part to constitute a substantially closed but loose connection for the end of the link, and an auxiliary chain carrying link having a pivotal connection with the first mentioned link and constituting in effect a closed link for the chain.

7. In a hame-fastener, a body part comprising oppositely disposed flat sides, a hook having a part projecting between the sides of the body part and secured to the latter, said projecting part of the hook being thin and constituting a spacing medium for the sides of the body part, a lever having a thin tongue to engage between the sides at the opposite end of the body part and mounted on the latter for pivotal movement, a link having opposite sides and a bearing part at one end, said lever having a projecting tail or lip intermediate its ends bent about said bearing part to constitute a substantially closed but loose connection for the end of the link, an auxiliary link, and a pivotal connection between said links, the links at their point of connection being substantially closed.

8. In a hame-fastener, a body part having a hook at one end thereof and a recess at its opposite end, a lever comprising an elongated handle part merging into a flat tongue or extension projecting laterally from the body portion of the handle, and which tongue is pivoted to the body part in said recess, a link, a bearing part carried thereby, and a bendable tail or lip projecting from the lever at the point of connection between the handle and the projecting tongue of the latter and bent about said bearing part of the link, the body part having a cutout por-

tion constituting a seat for the reception of 40 said tail or lip and link connection.

9. In a hame fastener, a thin flat body part comprising oppositely disposed sides, a hook projecting from one end of the body part and secured thereto, a lever having a 45 relatively thin tongue to engage between the sides at the opposite end of the body part and mounted for pivotal movement, a link having opposite sides and a bearing part, said lever having a projecting tail or lip 50 intermediate its ends bent about said bearing part to constitute a loose connection for the end of the link, and a chain carrying member at the opposite end of the link.

10. In a hame fastener, a body part comprising oppositely disposed flat sides, a hook having a part projecting between the sides of the body part and secured to the latter, said projecting part of the hook being thin and constituting a spacing medium for the 60 sides of the body part, a lever having a thin tongue to engage between the sides at the opposite end of the body part and mounted to the latter for pivotal movement, a link having opposite sides and a bearing part at 65 one end, said lever having a pivotal connection with said bearing part of the link, and an auxiliary link having pivotal connection with the first mentioned link, the auxiliary link being substantially closed at its point 70 of connection.

In testimony whereof I affix my signature in presence of two witnesses.

FRED W. COVERT.
